Henry Dreyfuss, New York, N.Y., assignor to American
Machine & Foundry Company, a corporation of New
Jersey

Application September 18, 1958, Serial No. 52,685

Term of patent 14 years

(Cl. D9—2)

The figure is a perspective view of combined cleaner and polisher for bowling balls or the like showing my new design.

The side not shown is substantially the same as that shown in that the design is substantially symmetrical.

I claim:

The ornamental design for a combined cleaner and polisher for bowling balls or the like, as shown and described.
